DESIGN FOR A CABINET

Emmett G. McQuinn, New Castle, and William J. Conwell, Elwood, Ind., assignors of one-half to The Hoosier Manufacturing Company, New Castle, Ind., and one-half to G. I. Sellers & Sons Company, Elwood, Ind.

Application November 30, 1934, Serial No. 54,212

Term of patent 3½ years

To all whom it may concern:

Be it known that Emmett G. McQuinn and William J. Conwell, both citizens of the United States, residing at New Castle, county of Henry, State of Indiana, and Elwood, county of Madison, State of Indiana, respectively, have invented a new, original, and ornamental Design for a Cabinet, of which the following is a specification, reference being had to the accompanying drawing forming a part thereof.

The single view in the drawing is a perspective view of a cabinet showing our new design.

We claim:

The ornamental design for a cabinet as shown. In testimony whereof we affix our signatures.

EMMETT G. MCQUINN.
WILLIAM J. CONWELL.
